Primary Examiner—Donald P. Walsh**Assistant Examiner**—Jeffrey Asch**Attorney, Agent, or Firm**—Herbert Dubno; Ronald Lianides**[57] CLAIM**

The ornamental design for an advertisement pillar or similar article, as shown and described.

DESCRIPTION

FIG. 1 is a front perspective view of an advertisement pillar or similar article showing my new design;

FIG. 2 is a rear elevational view thereof;

FIG. 3 is a left side elevational view, the right side being a mirror image thereof; and,

FIG. 4 is a top plan view thereof.

FIGS. 2-4 have been shown on a reduced scale with respect to FIG. 1.

FIG.1

FIG.2

FIG.3
